(57) **CLAIM**

I claim the ornamental design for the door knob sanitizer, as shown and described.

DESCRIPTION

FIG. 1 shows a front, top, and right side perspective view of a door knob sanitizer in accordance with the present invention;

FIG. 2 shows a front, top, and left side perspective view of the door knob sanitizer of FIG. 1;

FIG. 3 shows a front, bottom, and right side perspective view of the door knob sanitizer of FIG. 1;

FIG. 4 shows a front, bottom, and left side perspective view of the door knob sanitizer of FIG. 1;

FIG. 5 shows an elevational front view of the door knob sanitizer of FIG. 1;

FIG. 6 shows an elevational rear view of the door knob sanitizer of FIG. 1;

FIG. 7 shows an elevational left side view of the door knob sanitizer of FIG. 1;

FIG. 8 shows an elevational right side view of the door knob sanitizer of FIG. 1;

FIG. 9 shows an elevational top view of the door knob sanitizer of FIG. 1; and,

FIG. 10 shows an elevational bottom view of the door knob sanitizer of FIG. 1.

The broken lines showing in FIGS. 1-4 and 9 are included for the purpose of illustrating portions of the sanitizer or boundary and form no part of the claimed design.

1 Claim, 9 Drawing Sheets
